ADJUSTABLE GARMENT

Martin Goodman, New York, and David Lance,
Brooklyn, N. Y., assignors to The Neatform Co.
Inc., New York, N. Y., a corporation of New
York

Application April 11, 1939, Serial No. 267,234

5 Claims. (Cl. 2—41)

This invention relates to adjustable garments, particularly for supporting or molding a part of the body.

Adjustable garments having relatively movable portions with lacing for adjustment of the spacing between the ends of the portions, are already known. Such garments are used as health belts to relieve backache and fatigue, or to improve posture. They are also used in connection with many infirmities or ills. Adjustable garments are also employed to mold or control the figure, particularly at the abdomen. They are used by men to support the abdominal muscles, as well as by women in the form of girdles or corsets to mold the figure. Such garments have a space or gap between the ends with only lacing thereacross. This gap may show through the clothing, and is uncomfortable to the wearer. Moreover, when used for obesity, a part of the body at the lacing is not well controlled.

The primary object of the present invention is to generally improve adjustable garments of the foregoing character. A more particular object is to overcome the difficulties attendant upon the use of lacing. For this purpose we provide two relatively movable portions which overlap one another, one of said portions being transversely slit from a point near the top edge to a point near the bottom edge, in order to slidably receive the other portion. The ends are provided with adjusting straps which may be drawn tightly as desired. Such an arrangement eliminates the usual open gap or space between the ends of the movable garment portions, and it also eliminates lacing, but it is not altogether satisfactory because the long transverse slit tends to be drawn open at the middle by the pull of the adjusting straps. Accordingly, a further and more specific object of our invention is to overcome this latter difficulty, and this we do by connecting together the edges of the vertical slit by means of a series of spaced connections or links which prevent the slit from gaping open. Moreover, that part of the other garment portion which slidably passes through the transverse or vertical slit is itself longitudinally or horizontally slotted in order to receive the aforesaid links or connections.

Still another object of our invention is to provide a preferred method for making and assembling the parts of the adjustable garment, with a view to minimizing labor, and at the same time providing a garment of attractive appear-

ance and finish. More specifically, both of the relatively movable portions of the garments may be finished throughout their length along their upper and lower edges by smooth, continuous binding tapes, as will later appear.

In connection with a corset of relatively great vertical dimension, in contradistinction to a belt, it is desirable to be able to adjust the dimension of the upper part of the corset independently of the adjustment of the lower part of the corset, and a further object of our invention is to devise a corset which will provide independent adjustments of this character while at the same time retaining all of the advantages and features pointed out above.

To the accomplishment of the foregoing and such other objects as will hereinafter appear, our invention consists in the adjustable garment elements and their relation one to the other, as hereinafter are more particularly described in the specification and sought to be defined in the claims. The specification is accompanied by drawings, in which:

Fig. 1 shows an adjustable belt or girdle opened out to flat condition;

Fig. 2 is a horizontal section taken in the plane of the line 2—2 of Fig. 1;

Fig. 3 is a horizontal section taken in the plane of the line 3—3 of Fig. 1;

Fig. 4 is a horizontal section taken in the plane of the line 4—4 of Fig. 1;

Fig. 5 is a vertical section taken in the plane of the line 5—5 of Fig. 1;

Figs. 6, 7, 8 and 9 show successive stages in the manufacture of the garment of Fig. 1; and

Fig. 10 shows a corset embodying features of the present invention.

Referring to the drawings, and more particularly to Fig. 1, the garment comprises relatively movable or adjustable portions generally designated 12 and 14. These portions overlap, and the amount of overlap may be controlled by means of adjusting straps 16 and 18. The garment here shown is of the front hooking type, and is provided with appropriate clasps such as the hooks 20 and eyes 22 for connecting the ends of the garment together at the front. The ends of the adjusting straps 16 and 18 are brought around toward the front of the garment and are readily accessible for adjustment by the wearer while wearing the garment.

The portion 14 is vertically slit at 24. This slit extends from a point very near the top of the garment to a point very near the bottom.

In fact, it extends for the full height of the garment except for the binding tapes 26 and 28. The end of garment portion 12 passes through the vertical slit 24. This end then converges or tapers, as is indicated at 30, for connection to the adjusting strap 18. Similarly, the end of portion 14 converges or tapers, as is indicated at 32, for connection to the adjusting strap 16.

With the arrangement as so far described, the slit 24 would be drawn open at the middle upon the application of tension to the adjusting straps 16 and 18. To prevent this, we provide cross-connections or links at the points 34 and 36, these connections extending from one side 5 of slit 24 to the other, and functioning to prevent separation or gaping of the slit. At the same time, a part of portion 12 of the garment is horizontally slit or slotted, as is indicated at 38 and 40, in order to receive the links 34 and 20 36 respectively. The length of the horizontal slots is made equal to the desired range of adjustment of the garment.

The garment is preferably stiffened by the use 25 of a suitable number of bones or stays distributed thereabout. These are most commonly disposed in vertical or generally upright position. In the case of the particular garment here illustrated, there are bones or stays at 42, 44, 46, 48, 50, 52, 54 and 56. The end bones 42 and 56 are especially desirable in order to stiffen the garment 30 at the front and also to reinforce the same at the hooks and eyes.

In addition to the foregoing, the garment is 35 preferably provided with bones or stays immediately at each side of the vertical slit 24 and at each end of the horizontal slits 38 and 40. Specifically, there are bones 58 and 60 on opposite sides of slit 24. The bone 60 is, in the present 40 case, supplemented by an immediately adjacent bone 62. The bone 58 is supplemented by a bone 64 disposed a short distance to the left of bone 58. The portion 12 of the garment is provided with a bone 66 at the right-hand end of the horizontal slits, and in the present case, a pair of bones 68 and 70 at the left-hand end of the horizontal slits. It will be understood that these bones localized at the slits function not only to stiffen the garment and to support the body in desired fashion, but also to help maintain the slit 45 parts of the garment in proper, flat condition.

As is usual in the case of garments of this 50 character, the garment is made up of a number of pieces appropriately patterned so that the garment will be properly form-fitting on the body. In the present case, the garment is made up of parts which are secured together by lines of stitching for seams shown at 72, 74, 76, 78, 80 and 82. Moreover, the vertical slit 24 constitutes 55 a line of separation between two separately patterned parts of the garment.

The construction of the garment may be further explained with reference to the sections shown in Figs. 2, 3, 4 and 5 of the drawings. Referring first to Fig. 2, it will be seen that the portion 14 of the garment is slit at 24, the sides of the slit being reinforced by the bones 58, 60 and 62. The portion 12 of the garment, or rather the broad straps defined by the horizontal 60 slits, pass through the vertical slit 24. The ends of these broad straps are defined and reinforced by the bones 66, 68 and 70. It will be evident that these limit the range of adjustment of the garment.

75 The construction at the cross-connections or

links will be seen on reference to Fig. 3. In that figure it will be seen that slit 24 is crossed by a preferably narrow tape or link 34, the ends of this link being sewed into the garment on opposite sides of the slit 24. It may, for example, be sewed by the same stitching that is used at the sides of the bones 58, 60 and 62. These lines of stitching hold the tapes which enclose or bind the stays in position.

The adjusting straps 16 and 18 are, of course, received in appropriate buckles. Referring to Fig. 4, it will be seen how buckle 84 is held by means of a reversely bent tape or broad strip of fabric 86, the ends of which are sewed into the garment by means of the regular lines of stitching used at the seam 82. A similar construction is used for the other buckle at seam 72.

Referring now to Fig. 5, it will be seen how the adjustable part of portion 12 of the garment is sub-divided into comparatively broad straps or webs of material, 88, 90 and 92 with slits 38 and 40 therebetween. This need not be done by slitting a single piece of fabric. Instead, three separate pieces of fabric are used, which pieces are bound at their edges, as is indicated at 94, 96, 98 and 100. Moreover, the top edge of piece 88 and the bottom edge of piece 92 are bound by tapes 102 and 104, respectively, which tapes are preferably long, continuous tapes extending throughout the length of the garment portion 12, as will 20 later appear.

The method of constructing and assembling the portions 12 and 14 of the garment may be explained with reference to Figs. 6 through 9 of the drawings. The portion 12 is first formed without its convergent or triangular end and without its top and bottom binding tapes. The straps 88, 90 and 92 are secured in place at one end, but are left open at the opposite end. The portion 14 of the garment is completed except for its top and bottom binding tapes. The convergent or generally triangular end part 32 is secured to the remainder of the portion 14 solely by means of the spaced links or connections (34 and 36 in Fig. 1).

The two garment portions are preliminarily assembled by passing the parts 88, 90 and 92 through the slit 24 of portion 14, as is indicated in Fig. 6. The convergent or generally triangular end piece 32 of garment portion 12 is then stitched to the broad straps or slidables sections 88, 90 and 92 of the garment, thereby interlocking the two garment portions 12 and 14 against separation, as is clearly shown in Fig. 7. Top and bottom binding tapes 102 and 104 of garment portion 12 are then sewed along the entire length 50 of portion 12, as is shown in Fig. 8. The ends of the vertical slit 24 are still open, and this sewing operation is therefore readily performed by appropriately turning away the corners of garment portion 14, somewhat as is schematically indicated at 106 and 108 in Fig. 8.

As a final step, the top and bottom binding tapes 26 and 28 are sewed along the entire length of garment portion 14. These tapes come outside the tapes 102 and 104, and operate to close the heretofore open ends of main vertical slit 24.

The adjusting straps 16 and 18 may be added at any convenient time. If the ends of the adjusting strap are to be confined within the ends of 70 the binding tapes, then the strap 18 is preferably added between the steps shown in Figs. 7 and 8 of the drawings, and similarly, the strap 16 is preferably added between the steps shown in Figs. 8 and 9 of the drawings. If, however, the 75

ends of straps 16 and 18 are to be sewed outside the binding tapes, then the straps may be added after the binding tapes have been sewed in place.

A modified form of the invention is shown in Fig. 10 of the drawings. The most important difference illustrated in Fig. 10 is the provision of independent adjustment for the upper and lower parts of a comparatively wide garment. Specifically, Fig. 10 illustrates a lady's corset which is substantial in height. The dimension of the upper part of the corset, or in other words, at the waist of the wearer, is controlled by adjusting straps 110 and 112. The dimension at the lower part of the corset, or in other words, about the hips and buttocks, is controlled by the adjusting straps 114 and 116. These adjustments are substantially independent of one another, and afford flexibility in figure control.

The essential change in the construction of the garment for this purpose will be self-evident from inspection of the drawings, it being merely necessary to pattern the end of garment portion 118 to form two convergent or generally triangular end pieces 120 and 122. Similarly, the end of the other garment portion 124 is so contoured as to form two convergent or generally triangular portions 126 and 128. Each of these convergent portions leads to one of the adjusting straps.

Another difference illustrated by the garment of Fig. 10, is the provision of side opening rather than front opening. Specifically, the row of eyes 130 and the mating row of hooks 132 are so located as to come at the side of the wearer. The boned portion generally designated 134 then comes at the front or abdomen of the wearer, and the overlapping or adjustable portion generally designated 136 comes at the back of the wearer.

It will be understood that the desired adjustment is provided, as before, by means of a main vertical slit 138 extending all the way from the top to the bottom of the portion 124 of the garment, and by a series of spaced horizontal slits 140, 142, 144 and 146, which receive links or connections extending across the vertical slit 138. In the present case, however, because of the greatly increased vertical dimension of the garment, four such cross-links are employed, instead of only two as in Fig. 1. The portions of the garment may be assembled as heretofore described, the slit parts of portion 118 being passed through the vertical slit 138 and then being connected by the end pieces 120 and 122. The portion 118 is then provided with its top and bottom binding tapes 152 and 156, following which the portion 124 is provided with its top and bottom binding tapes 152 and 154. The auxiliary pieces of binding tape 156 and 158 may be added at any convenient time, either before or after assembling together the two main portions 118 and 124 of the garment.

It is believed that the construction as well as the method of fabrication and use of our improved adjustable garment, will be apparent from the foregoing detailed description thereof.

With reference to both forms of the invention, it should be understood that while we have shown the connecting links exceedingly narrow, they may, if desired, be widened somewhat. It is for this reason that the longitudinal or horizontal cuts may preferably be considered to be slots rather than slits, and of course, if the links and slots are widened, then the straps between the slots are correspondingly narrowed. We prefer the present arrangement with narrow links be-

cause then the wide straps form a substantially continuous surface bearing against the body, and this leads to maximum comfort.

It will be understood that while we have shown the main transverse slit to be a vertical slit, this slit may, if desired, be disposed at an angle, in which case, of course, the ends of the horizontal straps or slits should also be stepped or disposed at a similar angle. We prefer to make the transverse slit vertical because the resulting construction is simpler than when using a sloping slit, and further, because we prefer to stiffen the edges of the slit with bones, and ordinarily, it is desired to dispose these bones in upright position. If, however, in any particular case it is desired to dispose the bones in a biased or sloping position, the slit may be similarly sloped.

It will also be understood that while we have shown each of the adjusting straps running to a buckle of its own, it is also possible to extend the adjusting straps entirely around the body and to provide one buckle on one of the straps for receiving the other strap. In the arrangement of Fig. 1 there would then be a single buckle instead of two, and in the arrangement of Fig. 10 there would be two buckles instead of four.

It will therefore be apparent that while we have shown and described our invention in several preferred forms, many changes and modifications may be made in the structures disclosed, without departing from the spirit of the invention defined in the following claims.

We claim:

1. An adjustable body supporting garment comprising two overlapping relatively movable portions, one of said overlapping portions being transversely slit, except for one or more spaced links extending across said slit to prevent the same from opening, the other of said overlapping portions being horizontally slotted for a distance 35 equal to the desired range of adjustment, said transverse slit in the first garment portion receiving the second garment portion, and said horizontal slots in the second portion receiving the connecting links of the first portion, the ends 40 of said overlapping portions terminating in adjusting straps.

2. An adjustable body supporting garment comprising two overlapping relatively movable portions, one of said overlapping portions being 50 slit from near its top edge to near its bottom edge, except for one or more thin spaced links extending across said slit to prevent the same from opening, the other of said overlapping portions being horizontally slit for a distance equal to the 55 desired range of adjustment, said vertical slit in the first garment portion receiving the second garment portion, and said horizontal slits in the second portion receiving the connecting links of the first portion, said overlapping portions beyond 60 said slits converging in width and terminating in adjusting straps.

3. An adjustable body supporting garment comprising two overlapping relatively movable portions, one of said overlapping portions being 65 transversely slit from near its top edge to near its bottom edge, except for one or more spaced links extending across said slit to prevent the same from opening, the other of said overlapping portions being horizontally slotted for a distance 70 equal to the desired range of adjustment, said transverse slit in the first portion receiving the second garment portion, and said horizontal slots in the second portion receiving the connecting links of the first portion, the ends of said over- 75

lapping portions terminating in adjusting straps, said garment being provided with a number of generally upright bones or stiffening stays at each end of the horizontal slots.

5. 4. An adjustable body supporting garment comprising two overlapping relatively movable portions, one of said overlapping portions being vertically slit, except for one or more spaced links extending across said slit to prevent the same from opening, the other of said overlapping portions being horizontally slotted for a distance equal to the desired range of adjustment, said vertical slit in the first garment portion receiving the second garment portion, and said horizontal slots in the second portion receiving the connecting links of the first portion, the ends of said overlapping portions terminating in adjusting straps, said garment being provided with a number of generally upright bones or stiffening stays including one or more bones at each side

of the vertical slit and at each end of the horizontal slots.

5. An adjustable body supporting garment comprising two overlapping relatively movable portions, one of said overlapping portions being transversely slit except for spaced links extending across said slit to prevent the same from opening, the other of said overlapping portions being horizontally slotted for a distance equal to the desired range of adjustment, said vertical slit in the first 10 garment portion receiving the second garment portion, and said horizontal slots in the second portion receiving the connecting links of the first portion, each end of said overlapping portions being shaped to form a plurality of convergences or 15 generally triangular extensions each terminating in an adjusting strap for independent adjustment of the upper and lower portions of the garment.

MARTIN GOODMAN. 20
DAVID LANCE.
